UNITED STATES PATENT OFFICE.

ORRA HUBBELL, OF INDIANAPOLIS, INDIANA.

COOKING RETORT OR KETTLE.

SPECIFICATION forming part of Letters Patent No. 757,555, dated April 19, 1904.

Application filed December 19, 1903. Serial No. 185,842. (No model.)

To all whom it may concern:

Be it known that I, ORRA HUBBELL, a citizen of the United States, residing at Indianapolis, in the county of Marion and State of Indiana, 5 have invented certain new and useful Improvements in Cooking Retorts or Kettles, of which the following is a specification.

In the construction of kettles for rendering or cooking material which is first subjected to 10 the intense heat of live steam and is to be immediately thereafter subjected to the cooling action of cold water it is desirable that the water may be introduced very quickly.

The object of my present invention is to produce a cheap but very efficient construction of 15 this kind, the invention residing principally in the peculiar construction of a head or cover-receiving annulus which may be readily secured to the upper open end of a vat or retort 20 of usual boiler-like construction.

The accompanying drawings illustrate my invention.

Figure 1 is a side elevation; Fig. 2, a partial vertical section, and Fig. 3 a plan.

25 In the drawings, 10 indicates a vat or retort, preferably cylindrical and having an open upper end. Secured to this open upper end is a cast annulus 11, provided at its upper end with a thickened portion 12, within which is cast 30 or otherwise formed an annular chamber 13, from which lead a plurality of openings 14, forming communicating passages between the annular chamber and the vat. Formed in the upper end of the annulus 11 is an annular 35 groove or recess 15, adapted to receive a suitable packing 16 and also adapted to receive an annular rib 17, formed upon the under side of a cover 18.

For convenience the cover 18 is hinged at 40 19 to the annular head 11 and is provided with a plurality of slotted ears 20, through the slots of which may extend fastening-bolts 21, provided with suitable nuts 22, the arrangement being such that the nuts may be partially 45 withdrawn and the bolts then swung downward

away from the cover, so that the cover may be thrown upward on its pivot.

Leading into the annular chamber 13, preferably at closely-adjacent points, are two pipes 23 and 24, which are provided with valves 23' 50 and 24', respectively. One of these pipes is connected to a suitable source of steam-supply and the other is connected to a suitable source of cold-water supply.

When the vat has been filled with material 55 to be treated, the cover may be secured in position and the steam then turned into the annular chamber 13, whereupon it will pass through holes 14 into the interior of the vat. At any time, even before the steam has been 60 cut off, the water may be turned into the same chamber, and it will issue through openings 14 into the vat.

The device described is extremely easy to construct, for the reason that no complicated 65 job of piping is required, and the apparatus is exceedingly efficient.

I claim as my invention—

1. The combination, with a retort having an open end, of an annulus secured to said open 70 end and provided with an internal chamber communicating with the interior of the retort, and supply-pipes leading into said chamber.

2. The combination, with a retort having an open end, of an annulus secured to said open 75 end and provided with an internal chamber communicating with the interior of the vat, supply-pipes leading into said chamber, a cover-receiving surface formed at the upper end of said annulus, a coacting cover, and 80 means for detachably securing said cover to the vat.

In witness whereof I have hereunto set my hand and seal, at Indianapolis, Indiana, this 15th day of December, A. D. 1903.

ORRA HUBBELL. [L. s.]
